UNITED STATES PATENT OFFICE.

CONRAD HUBERT, OF NEW YORK, N. Y.

PORTABLE ELECTRIC LIGHT.

1,047,525.

Specification of Letters Patent. Patented Dec. 17, 1912.

Application filed July 15, 1912. Serial No. 709,334.

To all whom it may concern:

Be it known that I, CONRAD HUBERT, a citizen of the United States, residing at the borough of Manhattan, city of New York, 5 in the county of New York and State of New York, have invented a certain new and useful Improvement in Portable Electric Lights, of which the following is a specification, reference being had therein to the accompanying drawings, forming part thereof.

My invention relates to portable electric lights, particularly those of small dimensions and convenient shape for carrying in the pocket or for holding or carrying about 15 in the hand when in use.

In such portable lights it has been found advantageous to employ double circuit-closing means capable of effecting a double control, one for short periods of illumination 20 and in which the parts, when released, automatically return to the open circuit position, and the other for more prolonged periods of illumination and in which the closed circuit position of the parts is maintained until the parts are manually restored 25 to open circuit position. Automatic return of the circuit-closing parts to open circuit position to thereby automatically discontinue the light is more convenient, more economical of current consumption, and more desirable for short or instantaneous 30 flashes of light. On the other hand, circuit-closing means in which the parts will indefinitely maintain either a closed circuit or 35 open circuit position, obviate the tiresome necessity of holding the circuit closed for long periods of lighting and increase the scope of utility by enabling the light to be conveniently laid down in lighted condition, 40 leaving both hands of the user free.

An object of my invention is to provide improved means for effecting the double control of the light above referred to.

Other more general objects of my invention are inexpensiveness of manufacture, 45 simplicity of construction, durability, non-liability of derangement, and convenience of operation.

Other objects and advantages of my invention will hereinafter appear.

My invention includes, in combination, a contact member controlled by a spring-returned push button or other automatic circuit-opening device, and a bodily slidably 55 circuit closer or other movably mounted member adapted to actuate the contact mem-

ber to maintain the circuit in either the open or the closed position.

My invention also includes novel features of construction and combinations of parts as will appear from the following description.

I shall now describe the portable electric light illustrated in the accompanying drawings embodying my invention and shall thereafter point out my invention in claims.

Figure 1 is a longitudinal section of the casing and circuit-completing means, the circuit being in the open condition. Fig. 2 is an elevation as viewed from the right in Fig. 1. Fig. 3 is a front elevation, partly in section and with parts omitted, the circuit being maintained in closed condition. Fig. 4 is an elevation as viewed from the right in Fig. 3. Fig. 5 is a vertical section of the casing as viewed from the left in Fig. 3.

Referring to the accompanying drawings, a flattened and rounded outer sheet metal casing 1 has a miniature incandescent electric lamp 2 threaded into a socket formed in the closed end of the casing and removable contains a battery 3, the open end of the casing being closed by a hinged door 4. The battery terminals are usual projecting resilient metallic contact strips or contact springs 5 and 6. The spring strip 5 extends across the end of the battery 3 in position to be directly engaged by the center terminal of the lamp 2 (Fig. 1), and the other contact strip 6 is exposed within the casing and projects in position to be engaged by a contact member movably mounted on the casing in electrical connection therewith and forming a part of the circuit-completing means from the battery to the lamp, the casing being electrically connected to the other lamp terminal at the lamp-socket.

In the portable electric light illustrated in the drawings, the movable contact member is an inwardly projecting stud 7, which is provided with a rounded head 8, which normally, or when the circuit is open, projects to the outside of the casing 1 (Fig. 1) through a circular aperture 9, suitably spaced from the closed end of the casing in the rounded portion thereof. The projecting rounded head 8 constitutes a push button, which may be directly engaged by the thumb or finger to move the contact stud 7 into contact with the exposed battery terminal 6. The movable contact stud 7 and push button 8 are shown as mounted on a leaf spring 10 near one end thereof. The

stud-carrying spring 10 is located within the casing and at its other end is secured to the casing by means of a rivet 11. The contact-making stud 7 passes through the 5 spring 10 and is retained in place by means of a collar 12, which may be either a separate ring forced over the stud 7 or may be formed of the material of the stud 7 by upsetting such material. The spring 10 will 10 automatically return the contact stud 7 and its push button 8 to the normal or open-circuit position shown in Fig. 1.

The circuit-closing means provided for actuating and locking the contact stud 7 in 15 circuit-closing or contact-making position when desired will now be described. A bodily slideable circuit-closing member 13 is mounted on the casing by means of lateral combined guide lugs and attaching lugs 20 which extend to the inside of the casing through parallel guide slots 14 (Figs. 3 and 5) provided in the casing between the push button aperture 9 and the spring-securing rivet 11, the guide lugs being turned over or 25 clenched at the inside of the casing and being slideable in the parallel guide slots or guideways 14. At the outside of the casing, the circuit-closing member 13 has at its 30 middle, opposite the attaching and guide lugs, a longitudinally rounded projection engageable by the thumb or finger for manual actuation, and above and below such rounded projecting portion has flat end portions slideable along the outer surface of 35 the casing 1. The stud-carrying spring 10 is of reduced width in its middle portion, thereby both giving increased flexibility and providing space for the guide lugs of the slideable circuit-closing member 13 (Fig. 5).

40 Normally, both in the open circuit condition of the light and also during the time that the battery circuit may be in closed condition by reason of continued manual pressure on the push button 8, the bodily 45 slideable circuit-closing member 13 will occupy the retracted position shown in Figs. 1 and 2. In this position of the slideable circuit-closing member 13, release of manual pressure on the push button 8 will permit 50 the spring 10 to automatically return the contact stud 7 and the push button 8 to the open circuit position shown in Figs. 1 and 2. If the slideable circuit-closing member 13, 55 when in the retracted position of Figs. 1 and 2, be pushed toward the closed end of the casing, its flat end portion adjacent to the push button 8 will, by reason of the rounded exposed surface of the push button, exert a cam action on the push button and 60 will force the push button inward in a direction of movement substantially at right angles to the direction of movement of the slideable circuit-closing member 13, bringing the inner end of the contact stud 7 into 65 contact with the exposed battery spring 6

and closing the circuit. Further or continued movement of the slideable circuit-closing member 13 will cause the flat end portion thereof to override the push button 8 and to be brought to a position across the path 70 of the push button so that the push button is locked in depressed position, thereby holding the contact stud 7 in inward contact-making position (Figs. 3, 4 and 5). The circuit will now be indefinitely maintained 75 in closed condition without any effort on the part of the operator, the resistance of the leaf spring 10 developing a friction such as will prevent accidental shifting of these parts. The circuit will remain closed until 80 the slideable circuit-closing member 13 is pushed to retracted position (Figs. 1 and 2) to release the push button 8 and permit the spring 10 to retract the contact stud 7 and open the circuit. 85

It is obvious that various modifications may be made in the construction shown in the drawings and above particularly described within the principle and scope of my invention. 90

I claim:—

1. A circuit-closer for a portable electric light, comprising, in combination, circuit-completing means including an automatically returning contact member and a push button for actuating it, and a slideably movable non-resilient circuit-closing member engageable with the push button to shift the contact member to contact-making position and to hold it there or to permit automatic 100 return of the contact member from contact-making position according to the position of the circuit-closing member. 95

2. A circuit-closer for a portable electric light, comprising, in combination, a casing 105 having guideways for a circuit-closing member, automatically returning circuit-completing means adapted to be manually maintained in circuit-closing position, and a bodily slideable circuit-closing member 110 mounted to slide along the guideways of the casing and arranged to shift the circuit-completing means to contact-making position and to hold it there or to permit the automatic return of the circuit-completing means 115 from contact-making position according to the position of the circuit-closing member. 120

3. A circuit-closer for a portable electric light, comprising, in combination, a casing having guideways for a circuit-closing member, circuit-completing means including an automatically returning contact member carried by the casing and a push button for actuating the contact member, and a bodily slideable circuit-closing member mounted to 125 slide along the guideways of the casing and arranged to engage the push button to shift the contact member to contact-making position and to hold it there or to permit the automatic return of the contact member 130

from contact-making position, dependent upon the position of the circuit-closing member.

4. A circuit-closer for a portable electric light, comprising, in combination, a casing having guideways for a circuit-closing member, circuit-completing means including a spring-actuated contact member carried by the casing and a push button for actuating the contact member, and a bodily slidable circuit-closing member mounted to slide along the guideways of the casing and arranged to engage the push button to shift the contact member to contact-making position and to hold it there or to permit the spring-actuated return of the contact member from contact-making position, dependent upon the position of the circuit-closing member.
- 20 5. A circuit-closer for a portable electric light, comprising, in combination, a casing having guideways for a circuit-closing member, circuit-completing means including a spring-actuated contact member carried by the casing and a push button for actuating the contact member to contact-making posi-

tion, and a bodily slidable circuit-closing member mounted to slide along the guideways of the casing so that the paths of movement of the push button and of the slidable circuit-closing member cross each other, the push button and the slidable circuit-closing member being shaped for cam action of the slidable circuit-closing member on the push button thereby to shift the contact member to contact-making position, the slidable circuit-closing member having a surface shaped for engagement with the push button to lock the contact member in contact-making position upon continued sliding movement of the slidable circuit-closing member, a reverse movement of the slidable circuit-closing member unlocking the push button and permitting the spring-actuated return of the contact member from contact-making position.

In testimony whereof I have affixed my signature in presence of two witnesses.

CONRAD HUBERT.
